UNITED STATES PATENT OFFICE.

WILLIAM HASSALL, OF ASHBY-DE-LA-ZOUCH, ENGLAND.

FURNACE FOR KILNS.

SPECIFICATION forming part of Letters Patent No. 508,136, dated November 7, 1893.

Application filed August 10, 1893. Serial No. 482 795. (No model.)

To all whom it may concern:

Be it known that I, WILLIAM HASSALL, of Shelbrooke House, Ashby-de-la-Zouch, in the county of Leicester, England, have invented 5 certain new and useful Improvements in Furnaces or Fireplaces for Pottery and other Kilns, of which the following is a specification.

The object of this invention is to improve the heating of pottery and other kilns or 10 ovens, and to this end the invention consists in a novel construction or arrangement of furnace or fire place for use with such kilns, whereby both greater efficiency and economy in operation are obtained than heretofore.

15 In order that the invention may be clearly understood, I will now proceed to describe it in full, reference being had to the accompanying drawings, in which—

Figure 1 is a partial transverse sectional elevation of a pottery kiln, showing two furnaces or fire places constructed according to this invention. Fig. 2 is a similar view, showing a slight modification in the distribution of the air to support combustion. Fig. 3 is a vertical longitudinal section of the furnace or fire place, on an enlarged scale. Fig. 4 is a vertical transverse section, on the line $x-x$, Fig. 3, and Fig. 5 is a similar section on the line $z-z$, Fig. 3.

30 A, Figs. 1 and 2, represents the kiln proper, which is provided with a perforated floor B, through which the hot air and gases descend to an annular flue C in the base, in connection with a chimney or exhauster. In Fig. 2, 35 I show a central chamber D, to which cold air is introduced, and from which it passes by pipes crossing the annular flue C, to the furnaces, a number of which are arranged around the kiln in the manner well understood. All 40 the parts so far mentioned are known.

The new furnace or fireplace is designed to burn either solid or gaseous fuel, and while combustion of the fuel will be greatly improved, the furnace will be under perfect control, when in operation, so that the attendant will be able with facility to regulate the temperature, according to requirements. Hitherto the results of using gaseous fuel have not been satisfactory, the chief objection being 45 that it more or less blows and stains the goods, thus causing waste and loss.

By my present invention, I overcome the

difficulties previously experienced in gas firing; in fact, the new furnace or fire place becomes practically, when solid fuel is used, a 55 gas producer, and the gas produced is mixed in a suitable manner with air, and is burned as it enters the flue or "bag" in the kiln.

Referring now to the furnace, E is a rectangular fire chamber, formed of suitable material, say fire brick, with an opening F at its lower part, at back, to a flue or bag G of the kiln. Across the top, at the back, and for a short distance downward, on both sides, is a chamber H, in connection with the fire chamber E, by the opening J. The chamber H may also communicate with the fire chamber E by the small perforations K in the sides and back thereof.

50 I are air chambers placed one on each side of the fire chamber, and communicating therewith by the perforations L' in the walls, and to these chambers L, air is conveyed from outside the furnace by the passages a a, which are provided with means whereby the admission of the air may be regulated, or entirely 55 shut off, as desired.

55 c c are other air passages, which open at one end to the air, and at the other end to the other part of the fire chamber, and close to the 60 opening J. These passages are also provided with means to regulate the supply. The air, on entering the fire chamber E by these passages c c, divides, one part being drawn downward across the fire, to produce combustion 65 of the fuel, thus also serving to draw the heat away from, and to keep the front of the furnace cool, and the other part passing by the opening J into the chamber H. A comparatively small portion of this air passes into the 70 fire chamber E by the small openings K, but the bulk, which has become highly heated by contact with the walls of the fire chamber, passes downward behind the fire chamber, and escapes by the passages K', at the bottom 75 of the chamber H, into the opening F, where it meets with the carbonic oxide and other inflammable gases produced from the burning fuel, and causes these later to burst into flame, 80 producing thereby intense heat in the kiln, 85 without smoke.

90 M are the fire bars, or, it may be, a perforated plate, and N is the ash pit, which is provided with doors or other means whereby

it may be closed and rendered air-tight, when the fire lighted on the grate has burned up. The air supply then to the fire takes place only by the passages *a a* and *c c*, and can be 5 regulated to a nicety.

O is a suitable door by which the solid fuel is supplied to the furnace, and *P* is a similar door to the fire place. When gaseous fuel is used, the gas will be introduced to the ashpit 10 in any convenient manner, the perforated plate *M* before mentioned serving as a distributor.

In Fig. 2, the air supply passages *a* connect with the central air chamber *D*, instead of 15 with the outer air, and in order to prevent the stoppage of the air supply, by fuel dust falling into the passages *a* through the openings in the wall, I prefer that they shall enter the side of the chamber *L*, instead of the bottom, 20 as in Figs. 1, 3, 4, and 5. In these figures, the passages being open to the air, any accumulations can easily be raked out.

I claim—

1. The combination with a kiln, oven, or the 25 like, of a furnace having a fire-chamber open at back, at its lower part, to the kiln flue or "bag," an air chamber in either side wall, suitably supplied with hot or cold air, an air supply on either side to the upper part of the 30 fire chamber, a chamber *H* extending over the

top, and partly at the back and sides of the fire-chamber, and communicating therewith by an opening *J*, and by the restricted openings *K*, and also with the gas exit *F* by the passages *K'*, and an ash pit *N*, provided with 35 air tight doors, all substantially as herein shown and described, and for the purpose set forth.

2. In a furnace or fire place for kilns and the like, the combination with an inlet for air 40 on either side and near the top, of a chamber over the top and partly at the sides and back of the fire chamber, the said chamber communicating with the fire chamber at top by an opening in the crown, and at bottom by 45 the passages *K'*, as and for the purpose set forth.

3. In a furnace or fire place for kilns and the like, the combination with an exit for gas 50 at the lower part of the furnace, of a chamber over the top and partly at the sides and back of the fire-chamber, and communicating with the gas exit by the passages *K'* and with the fire chamber by an opening in the crown, as and for the purpose set forth.

WILLIAM HASSALL.
